US00D656296S

(12) United States Design Patent
Cavin et al.

(10) Patent No.: US D656,296 S
(45) Date of Patent:  *Mar. 27, 2012

(54) READY TO EAT SNACK PIECE

(75) Inventors: Nicole Cavin, Frisco, TX (US); Divya Paruchuri, Plano, TX (US); Michael Zbuchalski, Plano, TX (US)

(73) Assignee: Frito-Lay North America, Inc., Plano, TX (US)

(*) Notice: This patent is subject to a terminal disclaimer.

() Term: 14 Years

(21) Appl. No.: 29/381,217

(22) Filed: Dec. 16, 2010

(51) LOC (9) Cl. 01-01

(52) U.S. Cl. D1/128; D1/106

(58) Field of Classification Search D1/100-199; D30/160; D21/385-386; D24/101-104; D28/8.1; D11/90; 426/3-6, 76, 87, 89, 94-95, 426/100-104, 122, 128, 136, 138-139, 144, 426/249, 274, 293, 302, 305-307, 383, 438-442, 426/464-474, 460, 450-451, 496-497, 502-504, 426/512, 515-518, 543, 557, 549-550, 556, 426/559, 514, 660, 623, 619, 805, 806, 808, 426/499, 572; 428/15
